UNITED STATES PATENT OFFICE

163,080

DRINKING GLASS

William Yale Wilson, Western Springs, Ill.

Application June 24, 1950, Serial No. 10,730

Term of patent 7 years

(Cl. D36—8)

To all whom it may concern:

Be it known that I, William Yale Wilson, a citizen of the United States, residing at Western Springs, in the county of Cook and State of Illinois, have invented a new, original, and ornamental Design for Drinking Glass, of which the following is a specification, reference being had to the accompanying drawing, forming part thereof.

Figure 1 is a side view of a drinking glass, showing my new design, the side of the drinking glass opposite to that shown having the same appearance as the side of the drinking glass appearing in the drawing.

Fig. 2 is a bottom plan view thereof.

I claim:

The ornamental design for a drinking glass, as shown.

WILLIAM YALE WILSON,
